UNITED STATES PATENT OFFICE.

JOHN KNAPE, OF GRAND RAPIDS, MICHIGAN.

ADJUSTABLE SHELF-SUPPORT.

1,055,050.

Patented Mar. 4, 1913.

Application filed January 26, 1912. Serial No. 673,621.

To all whom it may concern:

Be it known that I, JOHN KNAPE, a citizen of the United States of America, residing at Grand Rapids, in the county of Kent and State of Michigan, have invented certain new and useful Improvements in Adjustable Shelf-Supports; and I do hereby declare the following to be a full, clear, and exact description of the invention, such as will enable others skilled in the art to which it appertains to make and use the same.

My invention relates to improvements in adjustable shelf supports and its object is to provide a cheap and strong device adjustable vertically at intervals and so constructed that it is readily applied to any flat surface as occasion may require, and also occupies but little space wherever used, and to provide the same with various new and useful features as hereinafter more fully described and particularly pointed out in the claim reference being had to the accompanying drawings, in which:—

Figure 1 is a perspective of a device embodying my invention; Fig. 2 a vertical section of the same with additional support shown therein to illustrate the method of attachment of the same to the fixed member; Fig. 3 is a plan view of my device; Fig. 4 a perspective of the adjustable member modified for additional strength. Fig. 5 a vertical section of the same; and Fig. 6 the sheet metal blank for forming the part as shown in Fig. 4.

Like numbers refer to like parts in all of the figures.

1 represents the wall of a bookcase or other support for the device showing a flat surface to which the same may be attached. The fixed part of the device consists of a strip of sheet metal the margins 2 of which are adapted to be secured in contact with any flat surface. The middle portion of this strip is formed outward to an extent of about double the thickness of the sheet metal of which the adjustable members are made and provided with transverse slots 4 at regular intervals. This middle portion has a flat outer surface in a plane parallel with the

side portions 2 and spaced apart from the support 1 at the rear. This raised portion forms a longitudinal channel at the rear of the device adapted to receive the upturned supporting hook 8 on the adjustable member. This member consists preferably of a flat plate of sheet metal normally adjusted horizontally and having two downwardly turned projections, 7, 7 spaced apart sufficient to embrace the raised portion 3 of the bar and preferably turned downward at right angles to engage the outer surface of the side portions 2 of the fixed member. The hook 8 is adapted to pass through any one of the horizontal slots 4 in the raised portion 3 of the bar and is turned upward at right angles in substantially the same plane as the projections 7 and engages the inner or rear side of the raised portion 3 of the bar in opposing relation to the projections 7 whereby the plate 5 is securely held in horizontal position, the downwardly projecting portions 7 forming a fulcrum considerably below the plane of the plate 5 and engaging the margins 2 which are rigidly supported; the plate will therefore not yield under considerably heavy loads. Thus a very strong device is secured. The outer corners of the plate 5 are also preferably provided with upwardly projecting spurs 6 which enter the under side of the shelf and prevent the same from slipping on the support.

For extra heavy loads, I prefer to reinforce the projections 7 by bracket-shaped braces 9 shown in Figs. 4, 5 and 6. These in the blank constitute lateral extensions of the plate 5 and are formed downward at right angles thereto with the rear end abutting against the downwardly turned projections 7 and securely support the same against a very considerable downward pressure on the plate 5.

Obviously if the braces 9 are used the projections 7 may be omitted and the ends of the braces directly engage the side portions 2 of the fixed member.

What I claim is:—

An adjustable shelf support, comprising a fixed member having side portions in the

same plane adapted to be secured to a flat surface and a raised middle portion provided with transverse slots and a plate having at one end an upturned hook to enter said slots and engage the rear of said raised portion and end extensions turned downward to embrace said raised portions and engage the front of said side portions and

also having side extensions turned downward and engaging the end extensions. 10

In testimony whereof I affix my signature in presence of two witnesses.

JOHN KNAPE.
